UNITED STATES PATENT OFFICE

2,474,252

COMBINATION CHAIR AND TABLE UNIT

Margaret C. Ivory, Massillon, Ohio

Application June 18, 1945, Serial No. 600,061

5 Claims. (Cl. 155—124)

1

This invention relates to a combination chair and table unit, and more particularly to such a unit of the foldable and collapsible type.

A primary object of this invention is the provision of an improved table unit characterized by folding legs, and having a plurality of collapsible chairs normally affixed thereto and adapted to be folded under the table top when not in use in order to form a relatively simple and compact unitary assembly.

Still another object of the invention is the provision of such a device wherein the chairs, when in unfolded position, are permanently secured to the table top, and wherein means are provided whereby the relative distance of the chairs from the table may be varied as necessary.

Still another object of the invention is the provision of an improved means in association with such a device for securely holding the folded chairs and legs in related assembly when the table is in folded position.

Still another object of the invention is the provision of an improved table and chair combination adapted for use as a card table, a dinette table, or the like, which, when in folded position, will occupy a comparative minimum of space, and which may be readily transported from place to place as desired.

Still another object of the invention is the provision of such a unit which will be sturdy and durable in construction, reliable and efficient in operation, and relatively simple and inexpensive to manufacture, assemble and utilize.

Other objects reside in the combinations of elements, arrangements of parts, and features of construction, all as will be more fully pointed out hereinafter and disclosed in the accompanying drawing, wherein there is shown a preferred embodiment of this inventive concept.

In the drawings, wherein like reference characters designate like parts throughout the several views:

Figure 1 is a bottom plan view of the device, certain of the chairs being shown in folded position, and certain others in extended position, and certain of the legs being correspondingly disclosed in folded position and the lower left hand leg being shown in extended position.

Figure 2 is a side elevational view of the construction shown in Figure 1, certain parts thereof being indicated in different positions of adjustment,

Figures 3, 4, and 5 are perspective views of certain constructional details, shown as enlarged, and

2

Figure 6 is an enlarged fragmentary view, partially in section and partially in elevation, showing a detail of a joint construction comprising an element of the instant invention.

Having reference now to the drawings, there is generally disclosed at 10 a table top, provided with a plurality of legs 11, at opposite corners thereof, each of the legs being pivotally secured as by means of pivots 12 between spaced lugs 13 secured to the underside of the table 10. As best shown in Figure 3, the brackets 13, provided with apertures 14 through which the pivot pins 12 pass, comprise portions of extending plate members 15, the inner extremity of each of which is provided with resilient clips 16, and the sides of which are upwardly turned, as at 17, to provide channels within which the legs are adapted to rest when in folded position. Aligned apertures 18 are suitably formed in the side walls 17 of each member 15, and provide guides for the outwardly turned extremities 19 (see Figure 1) of each leg support 20, the opposite extremity 21 of which is suitably secured to the inner side of the associated leg 11. Suitable screws 22, or the like, pass through associated apertures 23 and may be utilized for holding the plates 15 in related assembly with the underside of the table.

As best shown in Figure 1, the leg assemblies fold diagonally of the rectangular table top, and between adjacent diagonally inclined legs are positioned chair assemblies, generally indicated at 25.

Each of the chair assemblies 25 comprises a seat portion 26, to which are secured oppositely disposed pairs of legs 27, having transverse base bars 28 connecting the extremities of adjacent pairs, the legs 27 terminating in a flattened member 29 adapted to engage between a pair of spaced lugs 30, flanged as at 31 and secured in any desired manner to the undersides of the seats 26. Suitably aligned apertures in the members 29 and the lugs 30 permit the passage of pivot pins 32 therethrough in such manner that the pairs of legs may be folded inwardly beneath the seats 26.

As best shown in Figure 6, a flange 33 extends transversely between adjacent lugs 30 and forms a seat against which a shoulder 34 formed in the portion 29 is adapted to abut to prevent the passage of the pivotally secured legs beyond right-angled position with respect to the seat 26.

A back member 35 is also provided for each chair and is pivotally secured, as by means of pivots 36, to the seat 26. A suitable joint similar to that disclosed in connection with the legs 27

may be utilized to preclude the passage of the back member 35 beyond a predetermined angle relative to the seat portion 26.

Means are provided for securing the chair assembly 25 to the under surface of the table top, and take the form of links 37 terminating in flattened extending portions 38 and 38', the portions 38' being suitably pivoted by pivot pins 39 between depending lugs 40 secured to the underside of the front edge of the seat 26 at substantially the mid-point thereof. Each portion 38 is secured, as by a pivot 41, to a corresponding flattened portion 42 comprising the extremity of a second link 43, the inner extremity of which is secured between depending lugs 44, as by means of a pivot 44'. The lugs 44 are carried by a sleeve 45 slidable on a rod 46, secured in any desired manner to the underside of the table 10. Suitable coil springs 47 surround the rod 46 and abut the sleeve 45 at opposite extremities thereof, in order to yieldingly bias the sleeve towards an intermediate or mid-position upon the rod 46. As will be readily understood from Figure 1, a chair unit and its associated articulated linkage which is attached to the sleeve member 45 is flexibly secured to the table whereby it may be disposed in positions closer to or further from the normal position. However, in either position displaced from the normal position one of the spring means 47 will normally urge the linkage and the chair to its normal position.

Suitable spring clips 48, provided with flanges 49, are secured, as by screws 50, to the underside of the table adjacent opposite sides of the chair seat, and when the chair is folded, serve to overlie the chair seat and the portions of the back members 35 adjacent the pivot points thereof to secure the assembly to the underside of the table.

Additional clamp members 51 are also provided, and take the form, as shown in Figure 4, of transverse plates 52 apertured, as at 53, to accommodate screws 54 (see Fig. 1) and upstanding arms 55 provided with bends 56 forming resilient members adapted to overlie the curved portions 48 of adjacent back members 35 when the chairs are folded beneath the table top.

From the foregoing, the operation of the device should now be readily understandable. When it is desired to utilize the same, the legs are unfolded in the position shown in Figure 2, and all, or any desired number of the chairs extended to the position disclosed in Figure 2. The legs may be rotated about their associated pivots to support the chairs at the desired height above the ground, and the backs 35 may be suitably positioned, as indicated in Figure 2.

Conversely, when it is desired to fold the device for storage, the chairs may be returned to folded position, and held securely in position by the clamps 48 and 51.

As many embodiments may be made of this inventive concept, and as many modifications may be made in the embodiment hereinbefore shown and described, it is to be understood that all matter herein is to be interpreted merely as illustrative and not in a limiting sense.

I claim:

1. In a device of the character described, a table top, a plurality of legs pivotally secured to the underside of said table top, and a plurality of collapsible chairs pivotally secured to

the underside of said top and adapted to fold between said legs, the securing means including a pair of pivotally connected links, the opposite ends of said links being secured to said chairs and said table top, respectively, the end of said link secured to said table top being mounted on a sleeve, and a rod secured to the underside of said table top on which said sleeve is adapted to slide.

2. In a device of the character described, a table top, a plurality of legs pivotally secured to the underside of said table top, and a plurality of collapsible chairs pivotally secured to the underside of said top and adapted to fold between said legs, the securing means including a pair of pivotally connected links, the opposite ends of said links being secured to said chairs and said table top, respectively, the end of said link secured to said table top being mounted on a sleeve, and a rod secured to the underside of said table top on which said sleeve is adapted to slide, and spring means biasing said sleeve towards the mid-point of said rod.

3. In combination, a table top, a plurality of legs pivotally secured to the underside of said table top, a plurality of collapsible chairs adapted to fold between said legs, means pivotally securing said chairs to said table top including articulated linkages each pivotally connected at one end thereof to one of said chairs and at the other end thereof, guide members secured to said table top, said linkages being pivotally connected to one of said members for slidable and guided movement thereon.

4. In combination, a table top, a plurality of legs pivotally secured to the underside of said table top, a plurality of collapsible chairs adapted to fold between said legs, means pivotally securing said chairs to said table top including articulated linkages each pivotally connected at one end thereof to one of said chairs and at the other end thereof, guide members secured to said table top, said linkages being pivotally connected to one of said members for slidable and guided movement thereon, and resilient means biasing said members to an intermediate position on said guide from movement towards either end.

5. In combination, a table top, a plurality of legs pivotally secured to the underside of said table top, a plurality of ~~collapsible chairs~~ adapted to fold between said legs, means pivotally securing said chairs to said table top including articulated linkages each pivotally connected at one end thereof to one of said chairs and at the other end thereof, guide members secured to said table top, said linkages being pivotally connected to one of said members for slidable and guided movement thereon, and a pair of coil springs on each rod, said coil springs abutting opposite ends of each member.

MARGARET C. IVORY.
